UNITED STATES PATENT OFFICE.

FRANK D. SHEPHERD, OF SALT LAKE CITY, UTAH.

PUPPET-VALVE.

1,329,809.

Specification of Letters Patent.

Patented Feb. 3, 1920.

Application filed February 7, 1918. Serial No. 215,867.

To all whom it may concern:

Be it known that I, FRANK D. SHEPHERD, a citizen of the United States, and resident of Salt Lake City, in the county of Salt Lake and State of Utah, have invented a certain new and useful Improvement in Puppet-Valves, and do hereby declare that the following is a full, clear, and exact description thereof.

10 My invention relates to puppet valves for internal combustion engines, and more particularly to the spring means, and the parts associated therewith, for acting on the valve in opposition to the customary cam for lifting the valve, and setting forth the objects of my invention generally they are the reduction in size of certain of the parts concerned whereby the quantity of material required and the weight thereof may be 15 greatly reduced without any impairment of the efficiency of the mechanism whatever; economy of manufacture by simplification of the structure and otherwise, economy being secured in this way additionally to 20 that which is secured by reduction of material, and all without any impairment of the efficiency of the mechanism; ease and convenience of manipulation in assembling the parts and removing them for access to 25 the valve and to them when necessary; and to secure the maximum power from the fuel used in the engine; and for the attainment of these objects and others which will be understood by those skilled in the art when 30 the nature of the invention is understood from the specification and drawings, my invention consists in the improvements substantially as hereinafter specified and claimed.

40 In the accompanying drawings:

Figure 1 is a vertical section of enough of a gas engine to illustrate one embodiment of my invention;

Fig. 2 is a horizontal section on the line 45 2—2 of Fig. 1;

Fig. 3 is a bottom view of the spring container and the valve stem guide thereof shown in Fig. 1;

Fig. 4 is a view similar to Fig. 1, but with 50 the parts shown in side elevation and illustrating a form of dirt cap for the oil hole in the container that may be employed;

Fig. 5 is a view similar to Fig. 1 illustrating another form of my invention;

55 Fig. 6 is a top plan view of the construction shown in Fig. 5;

Fig. 7 is a view similar to Fig. 4 of the construction shown in Fig. 5 but with the valve head made separate from the valve lifting stem.

My invention is not limited in its application to any particular type or construction of engine, and it will therefore be understood that the engine construction shown in the drawings is merely illustrative and is shown in the drawings simply because it is desirable for the sake of completeness of illustration of my invention.

As the valve mechanism is the same for both intake and exhaust, I show in the drawings but one valve mechanism, and as my invention is not concerned with the valve lifting mechanism, I do not consider it necessary to illustrate any more of the latter than a portion of the stem through which the lifting mechanism acts to raise the valve periodically from its seat.

In the drawings, 10 designates a cylinder, 11 the piston therein, 12 the cylinder head, 13 the valve seat, 14 the valve head for controlling communication between the cylinder 10 and the chamber 15 (either the intake or the exhaust), and 16 the valve lifting stem.

In the cylinder head I provide an internally threaded opening 17 that extends from the outer end of the head into the port 18 controlled by the valve mechanism and screwed into said hole is one end of a cylindrical shell 19, a gas-tight joint being provided by packing or a gasket between a shoulder on the shell 19, and the outer adjacent surface of the cylinder head. The outer end of the shell 19 is closed by a cap 20 which has a downwardly extending flange 21 which extends over the outer end of the shell 19 on the outside and is screwed thereon, the interior of the flange being threaded and the exterior of the adjacent portion of the shell 19 being threaded for this screw connection. By applying the cap 20 to the shell in the manner described no portion of the shell is taken up by the connection between the cap and the shell, and thus the interior of the shell need be only large enough to accommodate the spring and associated parts, all as herein-after set forth, and thus the height or length of the shell 19 may be reduced and cost and weight lessened. A gas-tight joint is formed 105 between the inner side of the cap 20 and the outer end of the shell 19 by a gasket 22.

From the inner end of the chamber 23 which the shell 19 contains, an opening of considerably less diameter than the chamber 23 extends through the container and 5 in which is slidably fitted a stem 24 reaching at its inner end to the valve head 14 and at its outer end into the chamber 23, and said stem moves outward when the valve is lifted from its seat and it is the means of 10 transmitting to the valve the force of the spring means within the chamber 23 for seating the valve and yieldingly holding the head 14 to its seat. Within the chamber 23 and at the inner end thereof and in position 15 to act upon and with the stem 24 is a disk 25 which slidably fits the walls of the chamber 23 and between the outer face of said disk and the inner end of the cap 20, I interpose a plurality of concentric coil 20 springs 26, the springs being thus nested one within the other. I am thus enabled to use a shell or container that is very short compared with a construction employing a single spring, and yet the plurality of 25 springs enables ample spring pressure to be applied to the valve head 14 to move it to its seat and hold it there until lifted by the valve lifting mechanism. Moreover the nesting of the springs one within the other fills up the space within the chamber 23 and thus makes unnecessary the use of any special filling device to diminish the volume of 30 the chamber 23 for the purpose of preventing an accumulation of gas in any substantial quantity by leakage through the opening provided for the valve stem 24. Any gas that may find its way into the chamber 23 cannot escape therefrom into the atmosphere because of the gas-tight closure of the 35 outer end of the chamber 23 by the cap 20.

Preferably the disk 25 has an upstanding rim or flange 27 which makes of the disk a cup to receive the lower ends of the springs 26; and to prevent any cushion or suction 45 action between the disk 25 and the inner end of the chamber 23, I perforate the disk 25 with several holes 28 which allow the free passage of air from one side of the disk to the other during its movements.

50 In the interest of economy and weight it may be desired to make the container 19 of a material not hard enough to stand the wear of the stem 24. To enable this to be done I employ a bushing 29 of the desired hard material which contains the hole through which the stem 24 passes and slides, said bushing 29 being of the thimble form with a flange or head 30 at the end toward the valve head 14 seated in a recess 31 in 55 the inner end of the shell 19. My object in employing the head 30 and placing it in the position described is that by the pressure which it receives, it will be kept in place by the engine pressure and not displaced or 60 moved out of position. It can thus be

simply slipped into position in the container 19 by a gas tight fit and secured with all necessary tightness by calking over the edge of the recess 31 at several points so as to cause such edge to overhang the edge of the head 30 at such points and for that purpose the outer corner of the head 30 is chamfered or beveled off as shown. If preferred the bushing 29 as shown in Fig. 5 may be screwed into place gas-tight and held from 70 unintentional or accidental turning by the use of a center punch to upset the screw 75 thread.

For the application of oil to the sliding members, I provide in the center of the cap 80 20 an oil hole 32 which may as shown in Fig. 1 be closed by a ball valve 33 yieldingly held to its seat by the pressure of the outer end of the innermost coil spring 26 so that unless the valve is moved from 85 its seat for oiling purpose the air tight condition of the chamber 23 is maintained.

The exterior of the container 19 at mid length is flattened or polygonal and a portion of the cap 20 is on the exterior correspondingly formed, for the application of 90 a wrench or other turning tool.

In the forms of my invention illustrated in Figs. 1 and 4, the valve head 14 and the valve stem 24 are not integral or otherwise 95 connected but are separate; and as illustrated in Fig. 4 the oil hole 32 is closed by a cover plate 34 to prevent dirt finding its way into said hole 32.

In the form of my invention illustrated in 100 Fig. 5, the valve head 14 is integral with the lifting stem 160 and also with the stem 240 reaching from its upper side into the spring chamber 23, and a concaved fillet 35 is provided at the juncture of the head 14 105 and the stem 240, and to accommodate said fillet a correspondingly shaped recess 36 is provided in the inner end of the bushing 29 and a shoulder 37 is formed at the inner end of the recess 36 to cause the scraping off of any 110 carbon or other material on the stem 240, and prevent the same wedging or packing in said recess 36. As shown in Fig. 5 the disk 25 is separate from the stem 240 and fits over the reduced upper extremity 38 of said stem, and engages on its underside the shoulder formed on the stem by the reduction of its extremity, and the outer end of stem 240 is provided with means for the application of a valve grinding tool which may, as shown, 115 be a slot 39. The cap 20 closing the chamber 23 of the shell 19 of Fig. 5 is provided with an oil hole 40 which at its inner end has a beveled valve seat 41 for a conical valve 42 which on its inner side is engaged 120 by the innermost spring 26 and has an inwardly projecting stem 43 which closely fits the coils of said spring and thereby forms a guide or support for the latter, and is otherwise useful in that it takes up some of 125 130

the space within the chamber 23. It is formed at its inner end to receive a valve grinding tool as by means of a slot 44. Extending from the valve 42 outward in 5 the oil hole 40 said valve has a guiding stem 45 that is cruciform in cross section so as to provide channels or passages for the flow of oil when it is forced off its seat. In the construction shown in Fig. 5 the 10 outer end of the cap 20 is reduced and the polygonal formation is provided on such reduced portion for the application of the wrench or other turning tool.

In the embodiment of my invention shown 15 in Fig. 7 the valve head 14 is shown integral with the upper valve stem 240 but separate from the lifting stem 161; but the construction in other respects is the same as that 20 illustrated in Fig. 5 with the addition of a dirt cap 46 in the form of a split cup that fits friction tight over the end of the valve stem 45 projecting above the cap 20.

As will be evident from the various constructions illustrated in the drawing as embodying my invention, such invention is not 25 restricted to any precise construction and arrangement of parts and besides changes in detail of the order of those illustrated in the drawings, other changes in such respects 30 may be made and constructions may be employed that will embody only some of the characteristics of the structures illustrated in the drawings, and hence the scope of my invention is to be understood as having no 35 restrictions beyond what is imposed by the language of the appended claims.

Having thus described my invention what I claim is:

1. In an internal combustion engine, a 40 puppet valve controlling a port in direct connection with the cylinder, means to seat the valve comprising a valve stem, a closed container having a guide for the valve stem, a plurality of concentric springs substantially filling said container, a moving member within the container on which all the 45 springs simultaneously act and which engages the valve stem, said container having a portion that forms the stationary reaction member.

2. In an internal combustion engine, a 50 puppet valve controlling a port in direct connection with the cylinder, means to seat the valve comprising a valve stem, a closed container having a guide for the valve stem, a plurality of concentric springs substantially filling said container, a moving member within the container on which all the 55 springs simultaneously act and which engages the valve stem, said container having a portion that forms the stationary reaction member, said reaction member being a re-

movable cap having a flange fitting over the outer side of the container.

3. A puppet valve comprising a shell, a 60 plurality of nested coil springs within the shell, means for transmitting the force of all the springs to the valve, a hole through the outer end of the shell, and a valve at the inner end of said hole, said valve being 65 acted upon by one of said springs.

4. A puppet valve of the class described 70 having a spring inclosing chamber, a stem reaching from the chamber to the valve on the outside thereof, means to transmit the force of the spring through said stem to the valve, a bushing through which the stem passes having at its end toward the valve 75 a shell engaging enlargement.

5. A puppet valve of the class described 80 having a spring inclosing chamber, a stem reaching from the chamber to the valve on the outside thereof, means to transmit the force of the spring through said stem to the valve, a bushing through which the stem 85 passes having at its end toward the valve a shell engaging enlargement, said end of the bushing having a recess and the valve stem having a fillet toward the recess, and the bottom of the recess being of larger 90 diameter than the stem.

6. A puppet valve comprising a shell, a 95 plurality of nested coil springs within the shell, means for transmitting the force of all the springs to the valve, a hole through the outer end of the shell, a valve at the inner end of said hole, said valve being acted upon by one of said springs, and said valve having a stem extending into the coils of the spring which engages it.

7. A puppet valve comprising a shell, a 100 plurality of nested coil springs within the shell, means for transmitting the force of all the springs to the valve, a hole through the outer end of the shell, a valve at the inner end of said hole, said valve being acted upon by one of said springs, said valve having a stem extending into the coils of the spring which engages it, and the end of said stem being formed to receive a valve grinding tool.

8. A puppet valve of the class described 105 having a spring inclosing chamber, a stem reaching from the chamber to the valve on the outside thereof, means to transmit the force of the spring through said stem to the valve, a bushing through which the stem passes having at its end toward the valve a shell engaging enlargement or head, the outer corner of the head being beveled.

In testimony that I claim the foregoing I have hereunto set my hand.

FRANK D. SHEPHERD.
